UNITED STATES PATENT OFFICE.

WILLIAM J. STAFFORD, OF QUINCY, ILLINOIS.

STOVE AND RANGE.

1,160,780.

Specification of Letters Patent. Patented Nov. 16, 1915.

Application filed July 3, 1915. Serial No. 38,036.

To all whom it may concern:

Be it known that I, WILLIAM J. STAFFORD, a citizen of the United States, and resident of Quincy, Illinois, have invented certain new and useful Improvements in Stoves and Ranges, of which the following is a specification containing a full, clear, and exact description, reference being had to the accompanying drawings, forming a part hereof.

My invention relates to improvements in stoves and ranges, particularly the type known as combination stoves and ranges, in which either coal or gas can be utilized for producing heat.

The conventional stove of this type has the burners located in the base of the oven with the result that a smaller part of the base is operative when the heat is being supplied by the coal, and the products of combustion find their way into the ovens owing to the contracting or expanding or warping of the surfaces between the burners and the oven base. Furthermore in the stoves on the market to-day, products of combustion of the gas burners pass into the ovens to be heated and hence on to the food to be cooked or baked; this is highly undesirable. In some other stoves now on the market baffle plates are placed in the ovens when gas is the fuel; this materially lowers the space efficiency of the oven.

My device obviates all of these difficulties, in that the burners or source of heat are located on the outside of the oven in a recess between the oven and the ash-pit in such a manner as not to obstruct the flues around the oven when coal is the fuel and to distribute the heat as evenly as possible between the flues around the oven. No baffle plates are used, the stove being in preparation for either coal or gas fuel at all times.

With the above purposes in view, my invention consists in certain novel features of construction and arrangements of parts, as will be hereinafter more fully described pointed out in the claims and illustrated by the accompanying drawings in which—

Figure 1 is a longitudinal sectional elevation through the center of the range. Fig. 2 is a section along the line 2—2 of Fig. 1. Fig. 3 is an enlarged detail elevation of the burners shown in Fig. 1.

In the drawings numeral 4 designates the base plate and 5 the legs of the range. Mounted on the base plate 4 is positioned

the conventional oven 6, and the coal pouch 7 immediately over the ash pit 8. Between the coal pouch 7 and the ash pit 8 is positioned the rocker grate 9. The gas plates 10 are secured to the oven 6 by the web 11. Oven 6 is enveloped by the flues 12—13—14—15; 16 designates the conventional stack.

The wall 17 separating flue 15 from the coal pouch 7 and ash pit 8 is offset at 18 by the walls 19 and 20, leaving a space 21 into which the burners 22 and 23 are placed. When the burners 22 and 23 are in the position shown in Fig. 1 the flue 15 is unobstructed. About the center 24 of burner 22 burners 22 and 23 are permitted to rotate, the member 25 being secured to both burners by the rivets 26, and hence preclude movement of the burners with respect to each other. When the burners are rotated in the direction of the arrow in Fig. 1 to a horizontal position, burner 23 lies at the base of flue 15 and at the entrance to flue 14. The rotation of these burners is brought about by the rotation of the extended handle or knob 25'. The rotatability of these burners makes possible a more even distribution of the heat in the flues because burner 23, when in the horizontal position (as it must always be when gas is used) lies at the entrance to flue 14 and starts a heated stream of air immediately into flue 14, and burner 22 now unobstructed into flue 15 starts a heated stream of air up the flue 15. Flue 15 is blocked or restricted by the plate 27 at its upper extremity. Furthermore this positioning of the burners (the horizontal) prevents the heat from concentrating in the space 21, possibly burning the walls 19 and 20, and operating at a low efficiency. When coal is the fuel, the burners are placed in the position shown in Fig. 1, the heat originates in the pouch 7 and in the direction of the arrow passes through flues 12—13—14 and then through a baffled path (not shown) under the oven to the rear and up the stack 16.

When gas is the fuel the heated gases pass from the burner 22, up the blocked flue 15, on one side of the oven, and through flues 14—13—12 and stack 16 on the remaining sides of the oven.

28 designates a flue clean out.

29 designates air holes into the space 21 from the bottom of the range.

The burners can be made to remain sta-

tionary in the position shown in Fig. 1. When so made a damper 30, rotatable about a point 31 is so positioned that in the position shown by full lines in Fig. 1 the space 5 21 is sealed from the flues 14 and 15. The utility of this positioning of the damper resides in the fact that when coal is the fuel, air is precluded from entering the flues 14 and 15 through the air holes 29 and disturbing 10 the circulation of the products of combustion. When gas is the fuel, the damper is positioned horizontally thereby admitting a free access of air through the air holes 29. It will be discerned that by these means, the 15 objects stated elsewhere in this specification are accomplished.

What I claim is:

1. In a device of the character described, ovens, flues, said flues surrounding said 20 ovens, an offset at the juncture of two said flues, a source of heat rotatively secured in said offset, so that in certain positions of said source of heat, the flues will be unobstructed while in other positions one portion 25 of said source of heat will be at the entrance to one of said flues and another member of said source of heat will be at the entrance to another of said flues.

trance to one of said flues and another portion of said source of heat will be at the entrance to another of said flues.

2. In a device of the character described, ovens, flues, said flues surrounding said 30 ovens, an offset at the juncture of two said flues, a source of heat consisting of two hollow members of circular cross section rotatively secured at the geometric cross sectional centers at the extremities of one of the members so that in certain positions of said 35 source of heat, the flues will be unobstructed while in other positions one member of said source of heat will be at the entrance to one of said flues and another member of said 40 source of heat will be at the entrance to another of said flues.

In testimony whereof, I have signed my name to this specification, in presence of two subscribing witnesses.

WILLIAM J. STAFFORD.
